UNITED STATES PATENT OFFICE.

HOWARD ALBERT HEYNE, OF NEW YORK, N. Y.

SWITCH-THROWING DEVICE.

Application filed March 14, 1925. Serial No. 15,652.

This invention relates to switch throwing devices, an object of the invention being to provide an improved arrangement of electromagnets and levers for throwing the switch, and improved locking means for automatically functioning to lock the switch in either of its completely thrown positions. This invention has particularly to do with a switch throwing device especially designed for use in connection with toy railroads, and can be manufactured and sold in a very compact form so that it can be readily applied to the switch, but it is, of course, to be understood that I desire to protect my invention in a much broader sense, as it may be applicable for use in connection with railroads of any type.

With these and other objects in view, the invention consists in certain novel features of construction and combinations and arrangements of parts as will be more fully hereinafter described and pointed out in the claims.

In the accompanying drawings—

Figure 1 is a diagrammatic plan view showing my improved device in operative position;

Fig. 2 is a sectional plan view of my improved switch throwing mechanism;

Fig. 3 is a view in section on the line 3—3 of Fig. 1; and

Fig. 4 is a fragmentary plan view on a large scale illustrating more in detail the locking mechanism.

1, 1 represents the rails of a main track; and 2, the rails of a siding. 3 represents a combination switch point and frog pivotally mounted as shown at 4 and adapted to be moved to open or close either the main track or the siding, as the case may be. I shall refer to this combination switch point and frog as "the switch" in the description following, for convenience and to eliminate lengthy description.

My improved switch throwing device includes a platform 5 on which a pair of electromagnets 6 and 7 are supported. The preferred means of support comprises a sheet-metal casing 8 which is clamped around the electromagnets and provided with base flanges 9 secured to the platform 5 by bolts 10 and nuts 11, or by other securing means. 12 represents a switch throwing lever which is pivotally mounted between its ends on a post 13, and at its inner end is located between the cores 14 and 15 of the

respective magnets 6 and 7, so that it is adapted to be attracted by first one magnet and then the other when said magnets are energized, as will more fully hereinafter appear. The outer end of the lever 12 is provided with a series of openings 16 in any of which a rod 17 may be coupled, and this rod 17 is connected to the switch 3, as shown at 18, so that when the lever 12 is moved on its pivot the switch will be thrown, as will be understood. In addition to the lever 12, I provide two other or auxiliary levers 19 and 20 which project through slots 21 in casing 8 and are pivotally mounted at one end on posts 23 projecting upwardly from the base 5. These levers 19 and 20 are adjacent the outer ends of the respective cores 14 and 15 so that they are attracted by the magnets 6 and 7, respectively, as will be explained. The outer ends of the levers 19 and 20 are connected by links 24 with the lever 12. The levers 19 and 20 are made with slots 25 receiving the ends of the links 24, so that there is some lost motion between the links and the levers for a purpose which will hereinafter appear.

To lock and secure the switch in either of its operative positions, I provide improved locking means consisting of an arm 26, which is angular in form and which is pivotally connected at one end to the post 13, as shown at 27. Coil spring 28 connects the arm 26 with a post 13 so as to exert an upward and inward pull upon the arm. This arm 26 has a lug 29 at its upper free end adapted to project into either of a pair of recesses 30 at opposite sides of the lever 12 and hold the lever against pivotal retrograde movement. The arm 26 is also formed with a horizontally positioned cam plate 31 adapted to be engaged by a tongue 32 which is pivotally connected to the lever 12 as shown at 33. The function of this tongue is to engage the cam 31 and move the arm 26 in a direction to lower the lug 29 out of the path of movement of lever 12 so as to allow the latter to swing, and this tongue is moved by a pair of rods 34 which connect the tongue with the levers 19 and 20, respectively.

The operation of this switch throwing device per se is as follows: Assuming the parts to be in the position shown in Fig. 2, it will be noted that the lug 29 is in position to prevent the movement of lever 12 in one direction. When the electromagnet 6 is en-

ergized, the levers 19 and 12 will be directed toward the respective ends of the core 14 of said magnet 6. As the slot 25 in the lever 19 permits a certain amount of lost motion of said lever before it exerts pressure on the rod 34 and lever 12, the rod 24 will, upon the initial operation of the magnet, first throw the tongue 32 in a direction to engage the cam plate 31 and move the arm 26 and 10 its lug 29 out of the recess 30 and out of the path of movement of the lever 12. A continued operation will cause the lever 19, through the medium of the rod 24, to swing the lever 12 to the switch mechanism. When 15 the movement is completed, the tongue 32 will ride to a position on the cam which will allow the spring 28 to bring the lug 29 into locking position at the opposite side of the link 12. It will thus be noted that when 20 either magnet is energized it will attract at its opposite ends two of said levers, and that by reason of the lost motion between the levers 19 and 20 and the lever 12 the locking lug 29 will be swung out of the path of movement of the lever 12 before the latter 25 movement and will automatically return to locking position when said lever 12 completes its movement, hence the switch in both will be automatically locked against 30 accidental displacement.

While I do not, of course, limit myself to any specific mechanism for controlling the magnets, I have shown more or less diagrammatically one means which will properly function. On the base 5 I illustrate 35 electric terminals 35, 36 and 37 which are electrically connected in circuit with the respective magnets. One of these terminals is connected by wire 38 with a battery or 40 other source of electricity 39, the other side of said battery being connected by a wire 40 with a T-shaped lever 41. This lever 41 is held in normal position by springs 42 so as to space the ends thereof from fixed contacts 43 and 44. One of these contacts is 45 connected by a wire 45 with the terminal 35, and the other of said contacts 44 is connected by a wire 45 with the terminal 37. Thus when the lever 42 is swung in one 50 direction it will close the circuit and energize one magnet, and when thrown in the other direction will close the circuit and energize the other magnet. When the lever is released the springs 42 will hold it in position 55 to open both circuits.

I claim:—

1. A switch throwing device, including a pair of aligned electromagnets, a switch throwing lever located between the magnets 60 and moved in opposite directions by the attraction of the respective magnets, and auxiliary levers operatively connected to the first-mentioned levers and located in operative relation to and being actuated by the outer ends of the magnets.

2. A switch throwing device, including a pair of aligned electromagnets, three switch throwing levers, one located between the magnets and attracted by both magnets, the other levers located adjacent the outer ends 70 of the magnets and attracted each by a single magnet, and means operatively connecting the levers.

3. A switch throwing device, including a pair of aligned electromagnets, three switch 75 throwing levers, one located between the magnets and attracted by both magnets, the other levers located adjacent the outer ends of the magnets and attracted each by a single magnet, a pivoted arm carrying a locking 80 lug adapted to be located at either side of the intermediate lever, a spring holding said arm in normal position, a cam plate on the arm, a tongue adapted to engage the cam plate and pivotally connected to the intermediate lever, and means operated by the outer levers to swing the tongue and move the locking lug out of the path of the intermediate lever during the movement of the latter. 85

4. A switch throwing device, including a pair of aligned electromagnets, three switch throwing levers, one located between the magnets and attracted by both magnets, the other levers located adjacent the outer ends 90 of the magnets and attracted each by a single magnet, a pivoted arm carrying a locking lug adapted to be located at either side of the intermediate lever, a spring holding said arm in normal position, a cam plate on the arm, a tongue adapted to engage the cam plate and pivotally connected to the intermediate lever, means operated by the outer levers to swing the tongue and move the locking lug out of the path of the intermediate lever during the movement of the latter, and links pivotally connected to the intermediate lever and having a loose connection with the outer levers whereby the outer levers first move the tongue before 100 motion is imparted to the intermediate lever. 105

5. A switch throwing mechanism, including a base, a casing on the base, a pair of aligned magnets in the casing, three pivotally supported levers, one lever located between the magnets and attracted by either magnet, the other levers located adjacent the outer ends of the magnets, means operatively connecting the levers, means connecting the intermediate lever with a switch, and means for locking the intermediate lever in both extreme positions of movement. 110

6. A switch throwing device, including a pair of spaced apart magnets, a lever having a portion disposed between the magnets and being arranged to be actuated by either magnet, and means actuated by the movement of the lever for positively locking the lever in either of its shifted positions. 125

7. A switch throwing device, including a 130

pair of spaced apart magnets, a lever having a portion disposed between the magnets and being arranged to be actuated by either magnet, and locking means actuated by an initial movement of said lever for unlocking the lever and for subsequently locking it in its shifted position.

8. A switch throwing device, including a

pair of spaced apart magnets, a lever having a portion disposed between the magnets and being arranged to be actuated by either magnet, and locking means actuated by an initial movement of said lever in either direction for unlocking the lever and for subsequently locking it in its shifted position.

HOWARD ALBERT HEYNE.
